UNITED STATES PATENT OFFICE.

JOSEPH A. HOLIFIELD, OF MOBILE, ALABAMA, ASSIGNOR TO WHITE FUEL OIL ENGINEERING CORPORATION, OF NEW YORK, N. Y., A CORPORATION OF NEW YORK.

SELF-REGULATING ARC-CURRENT GENERATOR.

Application filed March 21, 1921. Serial No. 454,277.

To all whom it may concern:

Be it known that I, JOSEPH A. HOLIFIELD, a citizen of the United States of America, residing at Mobile, in the county of Mobile and State of Alabama, have invented certain new and useful Improvements in Self-Regulating Arc-Current Generators, of which the following is a specification.

My present invention relates to a means for generating current for an arc circuit and particularly for a welding arc circuit in which a novel type of electric current generator is employed having the characteristic of automatically regulating the voltage in direct proportion to the variations in resistance in the arc so that a substantially constant current is maintained in the arc.

The chief object of my invention is to accomplish the ends aforesaid in the simplest and most inexpensive manner possible and by means which in its operation will not involve an appreciable loss of current in connection with its regulating functions.

I have conceived that an electric generator with a single work circuit commutator and twin independent parallel fields co-operating with a single armature, one field being so excited as to maintain a substantially constant magnetic intensity, while the other field is variably excited responsive to variations in the resistance in the arc, will produce by the sum of the magnetic influence of its twin fields on the armature a current of substantially constant characteristics in the arc.

As a modification of this idea and for the purpose of enabling the use of a lower voltage generator, the set of fields in circuit with the arc can be compounded and differentially wound.

It is a further object of my invention to design the generator so as to be self exciting, thus enabling the same to be driven by any available source of power and to this end the generator is provided with an exciting commutator and winding.

A further advantage of my invention lies in the fact that by reason of the effect of the difference of the magnetic intensity of the twin fields on a common armature winding at the same time, all sparking of the brushes is eliminated under all kinds of varying and sudden changes in the arc.

In order that my invention in its preferred embodiment may be more clearly un-

derstood by those skilled in the art, reference is made to the accompanying drawings in which I have diagrammatically illustrated self-regulating generators embodying the several features of my invention above set forth in their simplest form.

In Fig. 1 I diagrammatically illustrate an arc current generator with twin independent parallel fields.

In Fig. 2 I illustrate diagrammatically the same type of generator with the fields in circuit with the arc having compound differential windings.

In Fig. 3 I show a generator similar to Fig. 2 with an exciting commutator and armature coil therefor, which makes it a self excited unit.

Similar reference numerals refer to similar parts throughout the drawings.

In the embodiment of my invention illustrated in Fig. 1, I show a shaft 1 driven by any suitable source of power and I mount thereon an armature 2. This armature is elongated to permit of its co-operation with twin parallel fields 3 and 4 which are independent of each other and which both exert a joint effect at the same time upon the same coil of the armature windings typically illustrated at 5. The armature core is preferably designed with a gap 6 between the independent sets of poles, but this is only preferable construction and is not essential. Current from any direct current substantially constant potential source is supplied by a conductor 7 to the field windings 3 surrounding the poles 8, the current returning over a conductor 9 through a rheostat 10. The generator has any standard type of commutator 11 connected in any normal manner with the armature windings and having its brushes 12 connected in series with the arc circuit 13 which includes electrodes 14 and 15 and also which includes, in series therewith, the field coils 4 surrounding the other set of poles 16. The twin parallel fields 3 and 4 are so wound as to produce opposite polarity and they should be so wound and proportioned as to allow a predetermined flow of current through the arc circuit 13.

In operation, with the arc circuit closed before striking the arc the independent fields approximately neutralize each other, the field 3 predominating and causing a current flow through the arc circuit of the

desired amperage at low voltage which is proportionate to the predominance of the fields 3 over the fields 4. Upon striking the arc, the voltage increases with the length 5 of the arc and as the resistance in the work circuit thus increases, the predominance of the fields 3 increases proportionately over the fields 4 with a resultant proportionate increase in the voltage of the current in the 10 arcing circuit, and as a result of these conditions this generator will automatically produce in the arcing circuit a variable voltage which will maintain the current at the arc substantially constant within the 15 normal limits.

In the compound differentially connected generator design shown in Fig. 2, the parts are all as described in Fig. 1, except that I place the rheostat 10 in a branch from conductor 7 and by a branch circuit 17 from the 20 same conductor I supply the constant potential D. C. current under control of a rheostat 18 to a differential winding 19 on the poles 16, these windings connecting with the return conductor 9. This generator is 25 of low voltage, the armature 2 being wound say for 25 volts as contrasted with a 50 volt winding for the armature in Fig. 1. In the operation of this type of machine, 30 with the arcing electrode short circuited, the series winding 4 predominates over the differential winding 19, producing opposite polarity in the twin fields and as a result of their neutralizing influences, a low voltage 35 current is produced in the arcing circuit. As the arc is drawn the series field windings 4 are weakened until they are substantially balanced by the winding 19 which occurs under working conditions when the 40 arc has been drawn to its normal length, whereupon the welding current is generated entirely by the magnetic strength of the fields 3. As the arc is extended towards its maximum limit the shunt fields 19 predominate and change the polarity of the 45 poles 16, whereupon both fields act jointly to increase the voltage in the welding circuit and this increase is throughout maintained automatically in direct proportion to the 50 resistance in the arc.

In Fig. 3 I show an embodiment of my invention which is especially designed for any type of drive, which necessarily involves the designing of the generator so that it 55 will be self exciting. In this design the windings of the twin fields are as described in connection with the low voltage generator (Fig. 2), but the field windings may be as in Fig. 1. In this arrangement the 60 armature shaft 1 carries the supplemental exciting armature 20 having brushes 21 connected in the supply circuit 7, 9, in Figs. 1 and 2. The commutator is connected to an armature winding, typically illustrated

by the coil 22, which extends only under the influence of the fields 3 which are of substantially constant magnetic intensity. The magnetic intensity of the series fields 4 will naturally vary with the resistance in 70 the arc. By use of the special exciting winding 22 the generator becomes self exciting and constitutes a self contained welding unit which can be used at any point 75 where any suitable power is available. 75

The sum of the strength of the twin fields upon the single armature winding or a winding that is common to the twin poles at the same time will in all designs vary the armature voltage in proportion to the resistance 80 in the work circuit. 80

In the design shown in Fig. 2, if the pole 8 equals plus 25 and pole 16 equals minus 20, the voltage at the brushes will be plus 5. When pole 8 equals plus 25 and pole 16 85 equals zero, the voltage would equal plus 25 volts, and when pole 8 equals plus 25 and pole 16 equals plus 20, the voltage would equal 45 volts. The voltage thus varies 90 throughout the range from the difference to the sum of the magnetic intensity of the two poles. 90

Owing to the effect of the difference of the magnetic intensity of the twin fields on a common armature winding at the same time, all sparking of the brushes is eliminated under all kinds of varying and sudden changes in the arc. 95

The detailed construction or arrangement 100 of parts can be widely varied without departure from the principle underlying my invention, which involves the utilization of independent fields to regulate by their joint control of the armature, with the regulating function taking place in the armature 105 itself by causing a bucking current to regulate the flow of current in the arc. 110

Having thus described my invention, what I claim as new and desire to secure by Letters Patent, is:—

1. A self-regulating electric current generator for a welding arc, comprising a single armature, a single commutator for the work circuit, twin fields adapted to exert their magnetic influence at different points 115 upon the same coil of the armature winding at the same time, and means to vary the relative value of the field energizing currents to regulate the voltage of the generator in proportion to the resistance in the arc and 120 maintain the current in the arc substantially constant. 120

2. A self-regulating electric current generator for a welding arc, comprising a commutating means, a single armature for the work circuit, twin sets of poles disposed to exert their magnetic influence simultaneously on the same coil of the armature winding, and field circuits for said sets of poles adapted to vary the sum of the magnetic in- 130

fluence of the twin fields on the armature in proportion to the resistance in the arc.

3. A self-regulating electric current generator for a welding arc, comprising a commutator, an armature, two sets of poles disposed to exert their magnetic influence on different circumferential zones of the armature, and an independent field circuit for each set of poles, one of said field circuits being excited by a substantially constant potential current and the other by the welding current.

4. A self-regulating electric current generator for a welding arc, comprising a commutator, an armature, a plurality of pole pieces disposed to exert their magnetic influence simultaneously on the same coil of the armature winding, a separate field circuit for each of said poles, and means to excite one field circuit by a constant exciting current and the other by a variable exciting current responsive to variations in resistance in the arc.

5. A self-regulating electric current generator for a welding arc, comprising a single commutator for the welding current, a single armature, two fields having independent pole pieces of opposite polarity disposed to exert their magnetic influence jointly and simultaneously on different parts of the same coil of the armature winding, means to excite one field to maintain its magnetic intensity substantially constant, and means to vary the magnetic intensity of the other field responsive to the varying resistance in the arc.

6. A self-regulating dynamo for generating current for an electric arc, comprising an armature, a single commutator for the work circuit, means to maintain a field of substantially constant magnetic intensity surrounding one end portion of the armature, means to maintain a field of magnetic intensity surrounding the other end portion of said armature which varies with the resistance in the arc.

7. A low voltage self-regulating dynamo for generating current for an electric arc, comprising an armature, a single commutator for the work circuit, twin fields for said armature arranged lengthwise of the armature to exert their magnetic influence on different transverse sections thereof, one having a substantially constant magnetic intensity and the other having differential compound windings, the magnetic intensity

of one winding being substantially constant and the opposed magnetic intensity of the other being variable responsive to the resistance in the arc, the sum of the magnetic intensity of the twin fields being proportionate to the said resistance in the arc.

8. A low voltage self-regulating dynamo for generating current for an electric arc, comprising an armature, a single commutator for the work circuit, twin fields for said armature arranged side by side lengthwise of the armature, one field having a single winding and the other having compound differential windings comprising a substantially constantly excited winding and an opposed variably excited winding, the variations in the latter being responsive to the varying resistance in the arc.

9. A self-regulating electric current generator for an arc, comprising an armature, an exciting commutator and a work circuit commutator, twin fields adapted to exert their magnetic influence at the same time on different portions of the same armature winding, means to excite one field to produce a substantially constant magnetic intensity, means to excite the other field to produce a magnetic intensity which varies in direct proportion to the varying resistance in the arc, and an exciting winding in the armature exposed only to the magnetic influence of said constant field.

10. In a dynamo-electric machine the combination with a main set of pole pieces and a second set of pole-pieces, an armature cooperating therewith, said pole-pieces spanning substantially the same armature conductors, means controlling the relative excitation of the respective sets of pole-pieces, whereby said generator is inherently regulated to vary the voltage thereof in accordance with external circuit conditions.

11. In a dynamo-electric machine the combination with a main set of pole-pieces and a second set of pole-pieces, an armature cooperating therewith, said pole-pieces spanning substantially the same armature conductors, of an exciting winding and a series winding disposed upon said respective sets of pole-pieces, said windings being wound differentially with respect to each other.

In testimony whereof I affix my signature.

JOSEPH A. HOLIFIELD.
